DRAFT REGULATOR

Joseph P. Kozak, Cliffwood Beach, N. J.

Application June 24, 1953, Serial No. 363,862

7 Claims. (Cl. 236—45)

The present invention relates to a draft regulator.

It is among the objects of the present invention to provide a novel draft regulator arrangement which may be readily assembled with normal air conduit construction and which will provide a predetermined and accurate draft control or regulation for regulating the flow of air into a flue.

Another object of the present invention is to provide a novel draft control or regulator which will not tend to become deranged because of a collection of dirt, soot or carbon, and which may be readily installed by unskilled workmen or the average home mechanic in horizontal or inclined vertical flues.

Still another object of the present invention is to provide a draft regulator or control which is simple to construct, economical to produce, efficient in operation, and of rugged and durable construction.

A further object is to provide a novel draft regulator or controller which will have an increased range and which will be readily applicable to different size flues and will operate efficiently over a wide range of drafts ranging from .02 to .08 inch or more if necessary.

Still further objects and advantages will appear in the more detailed description set forth below, it being understood, however, that this more detailed description is given by way of illustration and explanation only and not by way of limitation, since various changes therein may be made by those skilled in the art without departing from the scope and spirit of the present invention.

In accomplishing the above objects, it has been found most desirable to provide a fixed hinge or pivot mount for the oscillating control disc or vane.

By causing the vane to swing upon a fixed pivot or hinge, assurance is had that collection of dirt, soot or other materials will not interfere with ready movement of the vane and further assurance will be had that the hinge construction will be substantially automatic or self-cleansing.

A feature of the present invention resides in the fact that the vane is pivotally mounted off center and desirably with the major weight of the vane above center and with the vane being of reduced depth and width below the hinge mount.

Desirably a compensating calibrated adjusting weight is mounted upon the vane below the hinge or pivot mount so as to counter-weight the upper portion of the vane.

In one construction the hinge mount is a fixed rod extending substantially across the vane upon which the vane is suspended.

In an alternative construction the hinge mount is split and the shaft bearings consist of two studs which are mounted upon the frame for the vane and which project inwardly into bearing mounts upon the vane.

The positioning of the bearings on the vane with the shaft being fixedly mounted upon the housing ring provides a better balance at the bearing points.

It further permits greater freedom in swinging of the

2

vane as the bearing points remain free of soot, dirt or any other foreign material. Desirably the bearing points have an eccentric connection so that there will only be a line or point contact permitting the vane to swing in substantially frictionless manner.

The balance weights are mounted both forwardly and rearwardly of the vane on a shaft, the shaft extending through the lower part of the vane.

This shaft may be at an inclination to the vane.

10 Preferably the forwardly projecting portion of the shaft is graduated and has an adjustable weight which may be positioned at a desired calibration and fixed in adjusted position by a set screw.

By providing a notch or leveling device in the housing 15 or vane, it is possible readily to plumb up the draft regulator so as to align it most readily in a horizontal or vertical flue.

With the foregoing and other objects in view, the invention consists of the novel construction, combination 20 and arrangement of parts as hereinafter more specifically described, and illustrated in the accompanying drawings, wherein is shown an embodiment of the invention, but it is to be understood that changes, variations and modifications can be resorted to which fall 25 within the scope of the claims hereunto appended.

In the drawings wherein like reference characters denote corresponding parts throughout the several views:

Fig. 1 is a front elevational view of one form of draft regulator vane and collar mounting according to 30 the present invention, in position on a vertical flue, showing a continuous one-piece, fixed hinge rod or shaft.

Fig. 2 is a transverse vertical sectional view upon the line 2—2 of Fig. 1.

Fig. 3 is a transverse vertical sectional view similar 35 to Fig. 2, showing the vane in position substantially 90° away from the position of Fig. 2.

Fig. 4 is a rear elevational view of the vane and mounting collar as shown in Fig. 1.

Fig. 5 is a transverse horizontal sectional view upon 40 the line 5—5 of Fig. 1.

Fig. 6 is a fragmentary transverse vertical sectional view upon the line 6—6 of Fig. 1 upon an enlarged scale as compared to Fig. 1.

Fig. 7 is a transverse fragmentary vertical sectional 45 view upon the line 7—7 of Fig. 1 upon an enlarged scale as compared to Fig. 1.

Fig. 8 is a transverse sectional view upon the line 8—8 of Fig. 2.

Figs. 9 and 10 are respectively diagrammatic sectional 50 views upon enlarged scales showing alternative hinge plate mounts of the vane upon a hinge stud or hinge rod.

Fig. 11 is a front elevational view of an alternative construction similar to Fig. 1, but showing a split pivot rod with side fixed hinge stud shafts extending across the 55 entire lower part of the vane instead of the continuous hinge rod as shown in Fig. 1.

Fig. 12 is a transverse vertical sectional view upon the line 12—12 of Fig. 11.

Fig. 13 is a transverse vertical sectional view similar to 60 Fig. 12, showing the vane moved to a position of almost 90° away from that shown in Fig. 12.

Fig. 14 is a rear elevational view of the vane and collar assembly as shown in Fig. 11.

Fig. 15 is a transverse horizontal sectional view upon 65 the line 15—15 of Fig. 12.

Fig. 16 is a fragmentary vertical sectional view upon the line 16—16 of Fig. 11 and upon an enlarged scale as compared to Fig. 11.

Fig. 17 is a fragmentary vertical sectional view upon 70 the 17—17 of Fig. 11 and upon an enlarged scale as compared to Fig. 11.

Referring to Figs. 1 to 7, there is shown a vertical flue

or conduit A having a sleeve or thimble B which may receive the frame or housing C and the rotating vane D.

Fixed to the housing and frame is the through pivot shaft E which engages the bearing plates F mounted upon the swinging vane D. The vane carries the fixed weight G and the adjustable or movable weight H.

The collar or frame C consists of an outside flange 10 which abuts up against the end 11 of the sleeve or thimble B. The frame is also provided with an inturned flange 12 which closely fits inside of the outer end face 14 of the sleeve or thimble B.

Inturned from the flange 12 is the peripheral or concentric section 15 which, as indicated best in Figs. 1 and 4, has a spacing 16 from the upper peripheral edge 17 of the vane D. This short peripheral flange section 15 extends downwardly on each side to a point 18 at or adjacent the horizontal center line 19. This center line is substantially above the hinge line 19a.

The peripheral flange as is best shown in Figs. 1 and 4 has an inward enlargement below the center line 19, as indicated at 20, and has an oblique edge 21 and a vertical edge 22. It then extends downwardly to the circular portion 23. The spacing 16 is maintained at 24, 25 and 26 around the entire periphery of the vane D.

The fixed hinge rod E, as shown in Figs. 1 and 4 and particularly in Figs. 5 and 6, has a main hinge portion 28 with the side, right-angular bent portions 29 and the end flanges 30 which are riveted at 31 to the frame portions 20.

Referring to the vane D, the vane has a circular top portion 35 and a reduced width lower portion 36. The lower sides of the vane below the center line 19 and at the hinge line 19a will receive the base flanges 37 of the hinge plates F. These base flanges are riveted into position as indicated at 38. Both flanges 37 carry the rearwardly extending stop extensions 40.

The hinge plate, as shown in Fig. 1, also has an extension 39 (see particularly Figs. 1 and 4) which is the stop for the closed portion.

Alongside the rivet connections 48 there may be provided interfitting location openings 42 and embossments 43 which are best shown in Fig. 6.

The lower portion of the frame C is provided with an alignment ridge 55, which is vertically aligned with the alignment notch 56a on the upper part of the frame C.

The alignment is achieved by suspending a weighted cord or plumb bob across the notches 56a and 55 and when they are aligned the draft regulator will be in correct position in respect to the vertical on the flue A or sleeve B.

The weight-carrying shaft 56 extends obliquely through the vane C below the center line 19 and the hinge line 19a. It is held in place against rotation by lodgment in the recess 57 (see Figs. 3 and 7). The shaft 56 is mounted at the vane, and at its rear end it carries the fixed weight G. This weight G, made up of a series of annular blanks 59, is held in position by the screw 60.

The forward end of the shaft 56 on the other side of the vane plate D is graduated at 58 and it has a sliding weight M, which may be fixed in any adjusted position by the set screw 62.

A spring may also be provided to hold the sliding weight M in position. The graduation 58 will enable correct determination of the proper position of the sliding weight M, as shown in Figs. 2 and 3.

The shaft portion 28 extends through the circular openings 75 in the plates 40. It is to be noted that there is an eccentric line contact between the fixed hinge portion 28 and the plate 40 which is self-cleaning as the vane D swings.

The opening 75 for the shaft E may be varied as indicated at Figs. 9 and 10. In Fig. 9 the fixed shaft E' extends through the triangular opening 78 in the hinge plate extension 80.

In Fig. 10 the rectangular cross-section shaft E' extends through the triangular opening 85 of the hinge plate extension 86.

The extension 39 will act as a stop against the flange portion 20 when the vane D is in closed position with the flange 15, as shown in Figs. 2 and 4. In open position the corner 96 of the bearing plate extension 40 will strike the lower peripheral portion 97 of the casing structure C, as indicated best in Fig. 3.

The various shaft arrangement of Figs. 9 and 10 will all provide a fixed hinge with a relatively swinging hinge plate.

The shaft connections as shown in Figs. 1 to 10 give an automatic cleaning of the hinge contacts and they permit the hinge plates to swing upon a line contact or a limited contact face. By keeping the shafts fixed and permitting the hinge plates to swing, a much more reliable construction is obtained.

The vertical ridge 55 and the notch 56 will enable correct alignment of the damper or draft regulator in either horizontal, vertical or oblique flue, as shown in Fig. 1.

The construction as shown in Fig. 10 will provide a substantially frictionless bearing resulting from the single line contact of the bearing and bearing plate hole. This frictionless bearing provides this regulator with a dependable sensitivity.

In the embodiment of Figs. 11 to 17 there is shown a vertical flue M with a sleeve or thimble N which receives the housing Q having the swinging vane P. This swinging vane P swings on the split bearing rod or stub hinge rods U by the hinge plates R. There is provided a pre-set interior weight S and an outside adjustable weight T.

Referring to Figs. 11, 12 and 15, the housing Q has a circular outside flange 110 which fits against the end 111 of the thimble N. The peripheral flange 110 fits closely against the end of the sleeve or thimble 111. The housing Q is also provided with a peripheral interior flange 114 at the top of the housing and 115 at the bottom of the housing with the enlargements 116 at the sides of the housing Q. A continuous space 117, 118, 119 and 120 separates the flange 114-115-116 from the edges of the vane P.

The split hinge U as shown best in Figs. 14 and 15 is formed by the short stub hinge rods 130 which are fixedly held in the forwardly extending, central loop 131 and the rearwardly extending side loops 132 stamped out of the metal of each enlarged housing flange portion 116. The ends of the stub rods 130 abut the edges 133 of the flange portion 116.

The opposite ends of the hinge rods 130 extend into the recessed portion 129 of the vane P. The recessed portion may extend across the full width of the vane at the hinge axis.

The bearing plates R have the extensions 134 with the openings 135 through which the bearing rod U passes. These plates R have base flanges 136 which are riveted in position at 137 and have location openings and embossments 139.

The base plate 136 has an extension 140 which acts as a stop against the enlargements 116. The base plate 136 also has a rearward extension plate 143. The lower edges of the plate 143 abut and are stopped against the lower flange 115, as shown in Fig. 13, when the vane P is fully open.

The rear weight S may be formed of a nut 144 which may be mounted in adjusted position upon the threaded shaft 145 and may be locked into adjusted position by the lock nut 146. The adjustable weight T may be adjusted to any position on the forward, graduated shaft portion 147 and held in position by the set screw 148. The threaded shaft 146 where it passes through recess 149 in the vane P is held in position by the nut 150.

The draft regulator as shown may be made in a wide variety of sizes and it may be made in varying sizes, depending upon the diameter of the flues.

The installation of the present invention is particularly satisfactory in that it gives a wide range of adjustment and one size of regulator will function quite effectively with a considerable range of different size flues.

As many changes could be made in the above draft regulator, and many widely different embodiments of this invention could be made without departing from the scope of the claims, it is intended that all matter contained in the above description shall be interpreted as illustrative and not in a limiting sense.

Having now particularly described and ascertained the nature of the invention, and in what manner the same is to be performed, what is claimed is:

1. A draft regulator comprising a circular frame having a cylindrical rearwardly extending attachment and a front peripheral flange and a swinging vane horizontally pivotally mounted to swing within said frame, said vane having a relatively wide upper semi-circular portion and a relatively narrow downwardly extending rectangular lower portion and said peripheral flange having its inside edge closely conforming to but slightly spaced from the edge of the vane and having wide portions adjacent the upper edges of the sides of the lower portion, horizontally aligned inwardly extending pins permanently mounted in said wide portions at each side thereof and extending into the opening inside of said flange and angle flanges mounted on the back of said vane having flange portions with openings in which said pins are received, said flange portions being perpendicular to the plane of the vane and said vane having channels aligned with said openings to receive said pins, and said angle flanges having extensions, one extension serving to limit the opening position of the vane and another extension serving to limit the closing position of the vane.

2. The regulator of claim 1, said wide portions having loops stamped out extending forwardly and rearwardly to receive and bind said pins.

3. The regulator of claim 1, said vane having a forwardly downwardly inclined threaded bolt with adjustable weights at the end thereof mounted on said vane below said pivot mount.

4. A draft regulator comprising a circular frame having a cylindrical rearwardly extending attachment and a front peripheral flange and a swinging vane horizontally pivotally mounted to swing within said frame, said vane having a relatively wide upper semi-circular portion and a relatively narrow downwardly extending rectangular lower portion and said peripheral flange having its inside

edge closely conforming to but slightly spaced from the edge of the vane and having wide portions adjacent the upper edges of the sides of the lower portion, horizontally aligned inwardly extending pins permanently mounted in said wide portions at each side thereof and extending into the opening inside of said flange and angle flanges mounted on the back of said vane having flange portions with openings in which said pins are received, said flange portions being perpendicular to the plane of the vane and said vane having channels aligned with said openings to receive said pins, said angle flanges having sideward and rearward extensions respectively to contact the sides and the bottom of said peripheral flange and limit the opening and closing position of said vane.

5. A draft regulator comprising a frame and a swinging vane hingedly mounted to swing toward and away from the plane of the frame, hinging means on each side of the vane positioned substantially below the center of gravity and the geometrical center of the frame and the vane, said hinging means consisting of opposite short stud hinge pins fixed in the sides of the frame and projecting inwardly, hinge plates mounted on each side of the back of the vane having a base portion in substantially the same plane as the plane of the vane and permanently mounted on the back of the vane, said base having side extensions to act as stops to contact the sides of the frame and limit the closing movement of the vane, said base also having rear extensions extending transversely and normal to the side extensions to contact the bottom of the frame and limit the opening movement of the vane.

6. The regulator of claim 5, said hinge plates also having forward extensions in the same plane as the rear extensions having hinge openings into which said short stud hinge pins extend forming the side hinge mounts.

7. The regulator of claim 5, said vane having an embossed channel extending laterally across said vane to receive and form clearance for said hinge pins.
